UNITED STATES PATENT OFFICE.

HEBER ENSLEY BRADBURY, OF BANNING, CALIFORNIA.

DRAFT ATTACHMENT FOR PLOWS.

SPECIFICATION forming part of Letters Patent No. 379,676, dated March 20, 1888.

Application filed August 19, 1887. Serial No. 247,364. (No model.)

To all whom it may concern:

Be it known that I, HEBER ENSLEY BRADBURY, of Banning, in the county of San Bernardino and State of California, have invented 5 a new and Improved Draft Attachment for Plows, of which the following is a full, clear, and exact description.

My invention has for its object to provide a simple, inexpensive, and efficient draft attachment adapted more particularly for connection to gang-plows, but applicable also for use with other agricultural implements or machines and vehicles, to allow the draft of animals to be adjusted laterally to accommodate the work to be 15 done.

The invention consists in certain novel features of construction and combination of parts of the draft attachment, all as hereinafter fully described and claimed.

Reference is to be had to the accompanying drawings, forming a part of this specification, in which similar letters of reference indicate corresponding parts in all the figures.

Figure 1 is a side elevation of a gang-plow 25 with my improvement applied and partly broken away. Fig. 2 is a plan view thereof; and Fig. 3 is a vertical sectional elevation taken on the line xx , Fig. 2.

The frame A of the plow, its supporting- 30 wheels B C , and the plows proper, D D D , may have any usual or approved construction, and there may be more or less than three plows connected to the frame, as the size of the implement and the work to be done may require.

To the support side timbers, a' , of the frame 35 A are connected pairs of iron straps E E , between which are held the opposite ends of a draft-bar, F , formed preferably of two metal plates or bars, ff , which are arranged one di- 40 rectly over the other, and are held apart, to provide a space between them to accommodate the draft-block G and pulleys H I , by means of spacing-blocks, and the same bolts J J , which hold the ends of the draft-bar F to the straps 45 E , also fasten the outer ends of two metal brace rods or plates, K K , the inner ends of which are secured to the center bar, a' , of the frame A by a bolt, h , and whereby the draft-bar F has a very strong connection to and substantial sup- 50 port from the plow-frame.

The draft-block G is preferably made of metal and is fitted by its central portion, g , be-

tween the two parts ff of the draft-bar F , and the block is provided with rear shoulders, $g'g'$, and parts g^2g^2 , bent forward therefrom and overlapping the outer faces of the parts ff , the forward edges of which are overlapped by shoulders g^3g^3 on draft-block, to the forwardly-projecting end g^4 of which the doubletree L is connected by a link, l . Singletrees M N are 60 coupled to the doubletree to receive direct draft of horses to be hitched to them. It is obvious that with this construction the draft-block may be shifted laterally either way along the draft-bar F to adjust the line of draft to 65 any position required by peculiar formations of the ground surface to be plowed, or as other circumstances may require.

The pulleys H I are journaled on pins or shafts h i , respectively, to and between the 70 parts ff of the draft-bar F , near opposite ends of the bar, and around these pulleys chains or ropes O P , respectively, are passed. The forward ends of these chains are connected at o p to the opposite sides of the draft-block G , and 75 the rear ends of the chains are wound in reverse directions, respectively, upon the lower end of a vertical shaft, R , which is journaled in the plow-frame bar a' and in a step-bearing in a bent metal plate, S , fixed to the frame. 80

To the shaft R above the frame there is fixed, by a bolt or otherwise, a catch-plate, T , having at its periphery and upper face a series of radial notches, t , with any one of which the end u of a spring-actuated latch-lever, U , pivoted 85 at u' to the frame or to a metal plate, W , fixed thereto, is adapted to engage. The lever passes through a guide staple or keeper, w , fixed to the plate W , all as clearly shown in the drawings. 90

It is obvious that by turning the shaft R in one direction by grasping its hand-wheel r , and when the latch-lever is disengaged from the catch-plate, the draft-block G will be moved toward one end of the draft-bar F and one side 95 of the plow-frame, and by turning the shaft in the other direction the draft-block will be moved toward the other end of the draft-bar and other side of the frame, one of the chains O P unwinding from the shaft as the other 100 winds on it.

The draft-block may thus be very easily and quickly adjusted to any place along the length of the draft-bar and without unhitching the

horses, and the latch-lever U will lock into one of the notches *t* of the catch-plate T to hold the draft-block securely in any desired position. Consequently the draft on the implement may be regulated to a nicety to accommodate the lay of the land and assure the most effective operation of the plows by holding them properly to their work to cut furrows of uniform width and depth in any grade of soil.

10 The herein-described draft attachment is adapted for connection with other agricultural implements, machines, or vehicles where an adjustment or apportionment of the draft is desirable or necessary, as will readily be understood.

Having thus fully described my invention, what I claim as new, and desire to secure by Letters Patent, is--

1. A draft attachment comprising a transversely-ranging draft-bar fixed to the frame of a plow or other implement, machine, or vehicle, a draft-block fitted to slide along the draft-bar adapted to receive hitching devices, and a device for adjusting the draft-block along 25 the draft-bar and comprising chains or ropes connected to opposite ends of the draft-block and extended to a shaft, around which they are wound in reverse directions, and a latch device for locking the shaft against rotation, 30 substantially as described, for the purposes set forth.

2. A draft attachment comprising a transversely-ranging draft-bar fixed to the frame of a plow or other implement, machine, or vehicle, a draft-block fitted to slide along the draft-bar adapted to receive hitching devices, a device for adjusting the draft-block along the draft-bar and comprising chains or ropes connected to opposite ends of the draft-block and 35

extending to a shaft, around which they are wound in reverse directions, and a locking device comprising a notched plate fixed to the shaft, and a lever fulcrumed on the frame and engaging said plate, substantially as described, for the purposes set forth. 40

3. The combination, with the frame of a plow or other implement, machine, or vehicle, of a transversely-ranging draft-bar, F, fixed to the frame and formed with upper and lower parts, *ff*, a draft-block, G, fitted between said parts *ff*, and having shoulders at the edges thereof, pulleys H I, journaled on the draft-bar, a shaft, R, journaled on the frame, chains or ropes O P, connected at one end to opposite ends of the draft-block and at the other end to the shaft, 50 around which they wind in reverse directions, and devices locking the shaft against rotation, substantially as described, for the purposes set forth. 55

4. The combination, with the frame of a plow or other implement, machine, or vehicle, of a transversely-ranging draft-bar, F, fixed thereto and formed with upper and lower parts, *ff*, a draft-block, G, fitted between the parts *ff*, and having shoulders at the edges thereof, pulleys 60 H I, journaled on the draft-bar, a shaft, R, journaled on the frame, chains or ropes O P, connected at one end to opposite ends of the draft-block and at the other end to the shaft, 65 a plate, T, fixed to the shaft and notched at *t*, and a latch, U, fulcrumed on the frame and adapted to engage said notches, substantially as described, for the purposes set forth. 70
